Patented Apr. 16, 1912.

COLUMBIA PLANOGRAPH CO., WASHINGTON, D. C.

UNITED STATES PATENT OFFICE.

RICHARD H. SULLIVAN, OF LA CONNER, WASHINGTON.

SAW-TOOL.

1,023,341.

Specification of Letters Patent.

Patented Apr. 16, 1912.

Application filed August 11, 1910. Serial No. 576,688.

To all whom it may concern:

Be it known that I, RICHARD H. SULLIVAN, a citizen of the United States, residing at La Conner, in the county of Skagit and 5 State of Washington, have invented certain new and useful Improvements in Saw-Tools, of which the following is a specification.

This invention relates to tools which are 10 employed in the operation of sharpening and dressing the teeth of cross-cut saws.

The object of my invention, generally stated, is to provide a simple, durable and inexpensive device of this character whereby 15 the teeth of a saw may readily be put into efficient condition, even by an unskilled filer.

The invention consists in the combination in a saw-tool of various devices whose offices 20 are to guide a file in the sharpening of the cutting and raker teeth at selected bevels and angles; and also serving as a gage for the uniform swaging of the raker-teeth.

I attain these ends by the devices herein- 25 after described and illustrated in the accompanying drawings, in which—

Figure 1 shows a front elevation of the frame or body of the tool, partly broken away, and illustrates it as applied to the 30 jointing of a saw. Fig. 2 is a like elevation of the tool illustrating the raker-tooth dressing attachment connected thereto. Fig. 3 is a like partial elevation, showing the cutting-tooth dressing attachment in operative 35 connection with the tool-body. Fig. 4 is a rear elevation of the tool as represented in Fig. 3. Fig. 5 is an underside plan view of the tool body with a file, shown in dotted outline, secured 40 thereto for jointing purposes. Fig. 6 is a sectional view taken through 6—6 of Fig. 2. Fig. 7 is a perspective view of one of the file-guide elements, such as illustrated in Fig. 3.

45 The body of the tool, as best shown in Figs. 1, 4 and 5, is comprised of a horizontal member 10 having a web-element 11 depending from its rear edge and a depending element 12 is provided at the front edge of said 50 member. Intermediate the length of said

member, there is an opening 13 which is co-extensive with recesses provided in the aforesaid elements 11 and 12.

To afford strength and stiffness to the structure of the tool body reinforcing ribs, 55 such as 14, are provided. 15 is a block integral with said body and positioned in proximity to one end thereof in order to present a shoulder 15', see Fig. 5, against which the edge of tang 16 of a file is contacted when the file-blade 17 is placed in juxtaposition with the underside 10' of the web, and, by reason of the tapering form of the tang, the file, when shoved sufficiently toward the end of the body provided with 60 the block, the file is engaged between said block and the opposing surface of the web. With the file thus engaged and with the tool placed over a saw, as indicated in Fig. 1, endwise movements imparted to the tool 65 will cause the file to be carried along the points of the teeth for rendering them of proper relative heights or "jointed", as it is colloquially called.

Centrally of the web 11 and extending 75 downwardly from its top edge is a slot 18. Strips 19 and 20 protrude from the front face of the web, the former, 19, being disposed below the bottom of said slot and arranged horizontally while the other strips, 80 20, are vertical and are disposed at equal distances upon opposite sides of the slot. The function of said strips is to furnish the walls of a pocket whereinto the plates 21 or 22 of the attachments which I am about 85 to describe are, upon occasion, seated to maintain the same in operative position.

Referring to Figs. 2 and 6, the plate 21 is provided with an elongated aperture 21'. whose major axis corresponds with that of 90 the slot 18 to accommodate a headed screw-bolt 23 which is employed as a pivotal support for a pair of arms 24 and also serves, through the instrumentality of a wing-nut 25, to secure the latter in adjusted position 95 as well as fastening the plate 21 to the tool body. Said arms are formed with diverging upper portions whose opposing side faces 24' are machined to be in planes at right angles to the associated plate 21. 100

26 are brackets projecting forwardly from the plate 21 and terminate in upwardly directed extremities 26' which are provided with threaded holes for the reception of screws 27. Said brackets furnish abutments against which the arms 24 are supported and by adjusting the bolt 23 and retaining the arms 24 in contact with such brackets, it is evident that the angle of divergence of the arms may be regulated.

28 represents a thumb-screw extending through a threaded hole in a boss 29 provided in the body element 12 for the purpose of clamping a saw blade against lugs 21" provided upon the plate 21 and with a selected tooth to bear against the inner faces 24" of said arms.

The function of the above described attachment is to provide means for accurately dressing the raker teeth, R, of a saw. To accomplish which the arms 24 are first regulated, as explained, to the selected angular relation at which it is desired to slant the sides of the tooth notches and secured by the bolt 23. The tool is then placed with the surface 10' seated upon two or more of the previously jointed cutting-teeth C; and shifted thereupon to present one of the arm-faces 24' into position with respect to a sloping side of a raker-tooth notch so that the same, when filed down to coincide or be flush with the arm-face, will be dressed to its proper angle. The tool is then shifted to bring the face 24' of the other arm into position against the other sloping side of the tooth notch so that this side may be filed in like manner. After the raker-teeth have been thus correctly shaped, with the arms 24 as guides, the points are successively swaged to "hook" or turn them outwardly, as indicated by P in Fig. 2, to an extent that its extremity will respectively coincide with the upper peripheral edges of the adjacent screws 27.

45 Referring now to Figs. 3 and 4, the plate 22 is provided with a centrally disposed upwardly extending tongue 22' which serves as a support for a pair of legs 31. Said legs are each provided near its upper end with a 50 rearwardly directed stud 32 which extends through apertures 33 provided in said tongue, as shown in Fig. 4. Near the lower ends of the legs are provided slots 34 through which pass bolts 35 engaging in 55 threaded holes provided in the plate for the purpose of securing the legs at various angular relations when they are adjusted about the stud connections with the plate. The outer edges 31' of the legs are beveled 60 at angles suitable to the bevel of the cutting edges, of a saw's cutting-teeth. Upon the inner side of each of the legs is desirably provided a lug having a sloping face 31" against which the screw-head 36, pref-

erably conical, bears so that when the screw 65 is driven more or less into a threaded hole provided in the plate 22 this screw will coact with the bolts 35 in retaining the legs in rigid connection with the plate. The shank 36' of the above-alluded to screw is 70 of a length to extend through the slot 18 and to the rear of the web 11 to receive a winged nut 37 whereby the attachment just described is detachably secured to the tool body.

75 38 represents a strip projecting from the front of the plate 22 and is employed in conjunction with the legs 31 as a support against which a saw is clamped through the instrumentality of the screw 28, shown in Figs. 1, 5 and 6. By hingedly securing the legs 31 through the medium of the studs 32 it is apparent that the legs may be suitably swung to afford selected angles to which a cutting-tooth C of a saw is to be furnished. 80 The tool with the leg-carrying attachment applied, is employed by straddling the saw. With the teeth points supporting the tool, as before explained, it is moved so that a cutting tooth is located directly in front of 85 the pair of legs, and then the bevels are formed by filing the tooth upon opposite sides until the metal is removed down to planes which correspond with the planes of the leg surfaces 31'. It is to be understood 90 that the arms 24 and legs 31 are utilized as guides which limit and regulate the filing of the respective raker and cutting teeth; consequently they should be manufactured of a metal sufficiently hard to withstand the 95 cutting of the same by a file. The other parts, however, may be constructed of a cheaper material.

100 What I claim as my invention, is—

1. In a saw-tool, the combination with 105 the tool-body, of a plate provided with the elongated hole, a pair of arms, a screw extending through said arms and also through said hole and a slot provided in the body, a nut for said screw, a pair of brackets provided upon the said plate and coöperating with said screw and nut for supporting the arms in various angular relations, and screws extending through threaded holes in the respective brackets to furnish gages to 110 regulate the amount of swaging to be imparted to the raker-teeth of a saw.

115 2. In a saw-tool, the combination with the tool-body, of a plate provided with an elongated hole, a pair of arms, a screw extending through said arms and also through said hole and a slot provided in the body, a nut for said screw, and a pair of brackets provided upon the said plate and coöperating with said screw and nut for supporting the arms in various angular relations.

120 3. In a saw tool, the combination with the tool-body, of a plate, means to detach-

ably secure the plate to said body, a pair of members hingedly connected to each other and to said plate, and means for fixedly securing said members.

5 4. In a saw tool, the combination with the tool-body, of a pair of members hingedly connected to each other and to said body,

and means for fixedly securing said members.

RICHARD H. SULLIVAN.
